The ornamental design for a perforating gun contact device, as shown and described.

DESCRIPTION

FIG. 1 is a top, left perspective view of a perforating gun contact device according to a first embodiment.

FIG. 2 is a top, right perspective view of the perforating gun contact device of FIG. 1.

FIG. 3 is a right view of the perforating gun contact device of FIG. 1.

FIG. 4 is a left view of the perforating gun contact device of FIG. 1.

FIG. 5 is a front view of the perforating gun contact device of FIG. 1.

FIG. 6 is a back view of the perforating gun contact device of FIG. 1.

FIG. 7 is a top view of the perforating gun contact device of FIG. 1; and,

FIG. 8 is a bottom view of the perforating gun contact device of FIG. 1.

The broken lines depict unclaimed portions and form no part of the claimed design. Any portions not visible in the drawings form no part of the claimed design.
